(57) **CLAIM**

The ornamental design for a planter as shown and described.

DESCRIPTION

FIG. 1 is a front elevational view of a planter showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a second perspective view thereof;

FIG. 9 is an enlarged view of portion 9 shown in FIG. 2; and, FIG. 10 is an enlarged view of portion 10 shown in FIG. 9. The dash-dash broken lines illustrate portions of the planter that do not form part of the claimed design.

The dash-dot broken lines indicating lead lines and boundaries of enlarged portions shown in FIGS. 2, 8, 9 and 10 do not form part of the claimed design.

1 Claim, 10 Drawing Sheets(56)
